UNITED STATES PATENT OFFICE.

WALTER E. TRENT, OF RENO, NEVADA, ASSIGNEE OF ONE-THIRD TO H. C. CUTLER, OF RENO, NEVADA.

SEPARATING APPARATUS.

1,097,896.

Specification of Letters Patent. Patented May 26, 1914.

Application filed December 26, 1912. Serial No. 738,547.

To all whom it may concern:

Be it known that I, WALTER E. TRENT, a citizen of the United States, residing at Reno, in the county of Washoe and State of Nevada, have invented certain new and useful Improvements in Separating Apparatus, of which the following is a specification.

The hereinafter described invention relates to an improved apparatus for separating the solids from liquid and semi-liquid material generally, but more particularly such as slimes, pulp, pulverized ores, and cyanid solutions; the object of the invention being to simplify the construction of such class of machinery, to materially reduce the expense incident to the construction, operation and maintenance thereof, while at the same time securing a large working area for the material to be treated and by so doing materially increasing the working capacity of the machine.

To comprehend the invention reference should be had to the accompanying drawings, wherein—

Figure 1 is an end view of the apparatus, the hopper for the reception of the cake discharged from the filtering pans being in vertical section. Fig. 2 is a transverse sectional view of one of the filtering pans or trays removed from the apparatus. Fig. 3 is a front elevation of the apparatus, with parts thereof in section. Fig. 4 is a broken top plan view of one of the filtering pans or trays, illustrating the frame for the filter bed or medium situated therein and the spray pipe for supplying water to the surface of the filter bed for the lubricating thereof. Fig. 5 is a sectional end elevation of the apparatus taken on line $\alpha-\alpha$, Fig. 3 of the drawings, and viewed from the opposite end from that illustrated by Fig. 1 of the drawings.

In the drawings, the numerals 1 and 2 are used to designate a suitable form of spaced supporting blocks or pillars capable of sustaining the working parts of the apparatus, the same being preferably formed of concrete, upwardly projected from a base 3. Between the supporting pillars or blocks 1 and 2 is mounted for rotation a wheel frame 4 composed of end disks or plates 5—6 secured to a longitudinally disposed drive shaft 7, working in bearing boxes 8, mounted on the supporting pillars or blocks 1 and 2, and to the disks or plates 5 and 6 are secured

respectively the outwardly projecting or radial arms 9 and 9'. These arms are strengthened and connected one to the other circumferentially by means of the ring plates or braces 10, and the opposing arms of the respective disks or plates 5 and 6 are connected one to the other by means of the longitudinally disposed feed pipes 11, which pipes are closed at one end and each connected at the opposite end thereof by a branch pipe 12 extended from an annular launder 13 rigidly mounted on the drive shaft 7 and carried thereby. Material to be treated is supplied to the said launder 13 from any suitable source by means of a supply pipe 14 which is extended into the said launder through a feed opening 15 in the outer wall thereof, the liquid material admitted into the said hollow launder escaping therefrom successively, through the outlet openings 17 into the branch feed pipes 12, when the same are in a lowered position and entering into the feed pipes 11 from which it escapes through a series of discharge outlets 18 formed therein. These outlets 18 may be varied in size in accordance with the material to be treated, and the purpose of this discharge is to supply the requisite material or charge of the semi-liquid material into the trays or pans for the separation of the solid portions therefrom.

Between each opposing pair of radial arms 9 and 9' is suspended a swinging tray or filtering pan 19, each tray being provided with trunnions 19' and 20, mounted in bearings 20' carried by the outer end of each of the radial arms. These trays or filtering pans are preferably scoop shaped and so mounted as to normally lie in a horizontal position, the swinging action of the said trays or pans being similar in all respects to the cars or buckets of a "Ferris" wheel, in fact, the entire rotatable structure may be treated as to construction and operation as a "Ferris" wheel structure.

Within each of the swinging trays or filtering pans 19 is secured a filter, consisting of a suitable frame 20" composed of perforated pipes, which pipe frame is covered by a filtering medium or cloth 20'. The bottom layer of the filtering cloth for each filter or filter bed is given a coating of any suitable compound to render the same water-proof, and from one end section of the pipe frame 110

20" is extend³ through the trunnion 19' of the swingin⁴ trays or pans 19 a tubular extension 21, which is connected by a running joint 22 with the outer end of a 5 suction pipe 22'. These pipes at their inner end connect with the hollow end section 22^a of the shaft 7, Fig. 3 of the drawings, with which is connected by a stuffing gland 23 a suitable suction motor or air pump, not shown. Each filter tray or pan 19 is provided adjacent its rear upper edge with a perforated water spray pipe 22^a each of which is connected by an extension 24 passing through the trunnion 20 by a running joint 24^a with 10 a branch pipe 24' leading from the hollow end section 25 of the shaft 7, the said end section receiving water under pressure from a supply pipe 25' connected thereto by a stuffing gland 25^a. It will be understood that 15 air under pressure instead of water may be admitted through the pipe 24' and its connections onto the upper surface of the cloth 20^a of the filter within each tray or pan 19, although preference is given to water; and 20 it will be understood that each pipe 24' is connected to its spray pipe 23^a and each of the suction pipes 22' connected to its tray or pan 19 by a running joint in order that the said trays or pans may be free to swing 25 in order to maintain a horizontal position during the rotation of the frame structure in a vertical plan.

The frame structure is slowly rotated through the medium of a worm 26 on a 30 power shaft 26' meshing with a gear 27 secured to one end of the drive shaft 7, power being imparted to the shaft 26' in any suitable manner. Each of the suction pipes 22' is provided with a cut-off valve 28, the stem 35 thereof carrying a star cam 28' to be within the sphere of the spaced lugs 29 and 29'. When the star cam 28' engages with the lug 29 during the rotation of the filtering structure, the valve 28 is gradually thrown to 40 cut-off the suction through the pipe 22', and when the said star cam is brought into engagement with the lug 29', the same is thrown to open the said valve. Each of the branch water or air supply pipes 24' is also 45 provided with a controlling valve 30, the stem projecting therefrom carrying a star cam 30', which when placed into engagement with the spaced lugs 31 and 32 is gradually thrown to open and close the said 50 valve.

The water ejected onto the filter bed from the spray pipe 23^a lubricates the upper surface of the filtering cloth in order that the cake formed on the filtering medium within 55 the tray or pan 19 may readily discharge therefrom on the said filtering tray being swung downwardly as the same approaches the discharge hopper 32', into which the cake is discharged successively from the 60 filtering pans and removed from the said

hopper to a suitable place of deposit by means of the endless conveyer 33 situated in the bottom¹ of the said hopper and onto which the cakes are deposited.

In operation, the filtering trays are successively filled as carried in the present case below the point A by means of the feed supply pipes 11, which continue to discharge material into the filtering trays until the same are carried above the level of the point A', when the feed of material ceases. By this time the action of the suction means is brought into play and the liquid is drawn from the material through the filtering cloth, and perforated pipe frame 20', until all liquid has been withdrawn from the liquid material and the solids contained therein left on the filtering material in the form of a cake. By this time the valve 28 is closed and the valve of the pipe 24' 60 opened for admitting a spray of water onto the filtering bed for lubricating the same in order that the cake may freely slip therefrom on the tilting of the swinging tray or pan for the discharge of the cake therefrom into the hopper 32', the spray action being maintained until just prior to the swinging over of the said tray or pan. As the filtering tray with its formed cake approaches the discharge hopper 32', the arm 34 projecting laterally therefrom engages with the fixed brackets 34' and the said tray is gradually tilted or swung over into such a position as to cause the cake to slide therefrom into the discharge hopper 32', after which 65 the said tray, by reason of the weighted inner end thereof, swings back into position to receive another charge of material to be treated.

The described operation is successively 70 carried out with each of the series of swinging filtering pans of the rotatable structure, the operation of the filtering pans being independent of each other. The filtering operation for the semi-liquid material is carried on as a continuous operation, the solids deposited in each filtering tray being thoroughly washed prior to the discharge therefrom of the cake formed therein and all the liquid is withdrawn through the vacuum 75 chamber a of the filter prior to the discharge of the formed cake from the filtering trays.

It is obvious that as the filtering trays are of a length equal to the distance between the end disks 5 and 6 of the rotatable structure, that the capacity of the machine may be readily increased and decreased in accordance with the working capacity required, and that the number of filtering trays may be increased and decreased at will.

While the suction is in effect for drawing the liquid from the material under treatment into the vacuum chamber a of each filter and therefrom through the perforations of the pipe frame 20', the supply of 80

spray water discharged from the perforated pipe 23^a is cut-off. The supply of spray water is opened and remains open during the period that the suction is closed.

5 If so desired and found necessary during the operation of the apparatus, air may be forced from the suction pump through the suction pipe connections into the vacuum chamber *a* of the filtering bed or medium 10 and so applied under pressure beneath the cake resting thereon. Wash water if required may be applied in any suitable manner to the material while being treated.

I am well aware that changes and modifications may be made in the working parts and details of construction herein shown and described without creating a departure from the nature and scope of the described invention and I do not wish to be understood as confining or limiting myself to the construction herein illustrated.

Having thus fully described my invention what is claimed as new and desired to be protected by Letters Patent is:—

25 1. In an apparatus for the described purpose, the combination with an open frame mounted for rotation in a vertical plane, of a plurality of horizontally disposed swinging filter trays or pans suspended within said frame, means for maintaining each tray in horizontal position during the rotation of the frame, a filter medium held in each of said trays, an annular launder carried by the frame, a plurality of feed devices 30 extended from said launder for successively feeding solution to be treated into said pans during a portion of the rotary movement of the rotatable frame, valved controlled suction means connected with each filter tray 40 for drawing liquid through the filter medium thereof from the solution within the trays during a portion of the frame's rotation, valved controlled water supply means for admitting water for lubrication onto the 45 filtering medium of each tray during a stoppage of the suction means, devices for successively tilting or swinging the trays to discharge the cake therefrom, and mechanism for imparting rotation to the frame 50 structure.

55 2. In an apparatus for the described purpose, the combination with an open frame mounted for rotation in a vertical plane, of a plurality of horizontally disposed swinging filtering trays suspended within said frame, means for maintaining each tray in horizontal position during rotation of the frame, a filter consisting of a perforated pipe frame inclosed within a filtering bed 60 secured within each of the said pans, independent suction means connected with each filter tray for drawing through the filter thereof the liquid from the material within the trays for treatment during a portion of the frame's rotation, devices for sup-

plying water to the surface of the filter, an annular launder rotatable with the frame structure, means extended from said launder for supplying material to be treated successively to the swinging trays during a portion of the frame's rotation, devices for 70 tilting the trays during the rotary movement of the frame for the discharge of the cake therefrom, and mechanism for imparting continuous rotation to the said frame. 75

3. In an apparatus for the described purpose, the combination with an open frame mounted for rotation in a vertical plane, of a plurality of horizontally disposed swinging trays mounted within and carried by said frame, a filter secured within each of the trays, a supply launder rotatable with the frame structure, devices extended from said launder for independently supplying material to be treated to the said trays, independent controllable means for each tray for withdrawing the liquid from the material therein through the filter and applying a water supply to the upper surface of the said filter, mechanism for imparting 90 rotation to the frame of the apparatus carrying the swinging trays, and devices for successively tilting the said trays during the rotary movement of the frame for the discharge of the cake therefrom. 95

4. In an apparatus for the described purpose, the combination with an open frame mounted for rotation in a vertical plane, of a plurality of horizontally disposed swinging trays mounted within and carried by said frame, a filter secured within each of the trays, a launder carried by the frame, a plurality of feed pipes extended therefrom and connected to each of the swinging trays, for independently supplying material to be treated to the said trays, independent controllable means for each tray for withdrawing the liquid from the material therein through the filter and applying a water supply to the upper surface of the said filter, mechanism for imparting continuous rotation to the frame of the apparatus carrying the swinging trays, devices for successively tilting the said trays during the rotary movement of the frame for the discharge of the cake therefrom, a hopper situated at one side of the apparatus to receive the cake, and means within the hopper for removing the cake therefrom. 110 115

5. In an apparatus for the described purpose, the combination with an open rotatable frame structure mounted for rotation in a vertical plane, of a drive shaft to which the same is secured, a plurality of horizontally disposed filter trays journaled within said frame circumferentially, means for maintaining each of the filter trays in horizontal position during the rotary movement of the frame, a filter secured within each of the filter trays, a supply launder rotatable 120 125 130

- with the frame, a plurality of devices extending from said launder for independently supplying to each of said trays during a portion of the frame's rotation material to be treated, a valve controlled pipe leading from each filter, means for connecting each of said pipes with a source of suction, devices for successively actuating the valve of the controlled pipes for cutting off and 5 opening the suction through said pipe during the rotary movement of the frame structure, means for tilting the filter trays for the discharge of the cake therefrom, and mechanism for imparting rotation to the 10 frame structure.
6. In an apparatus for the described purpose, the combination with an open frame structure mounted for rotation in a vertical plane, of a plurality of horizontally disposed 15 swinging filter trays mounted circumferentially within the said frame structure, means for maintaining each filter tray in horizon-

tal position during rotation of the open frame, a filter head in each of said trays, independent controllable suction means extended from each of said filters, a launder for the material to be treated carried by the rotatable frame, a plurality of devices extended from said launder and independently connected to each of the filter trays for supplying material to be treated to the said filter trays, means for tilting the said trays during a portion of the frame's rotation for the discharge of the formed cake therefrom, and mechanism for imparting continuous 30 35 rotation to the frame structure.

In testimony whereof I have signed my name to this specification in the presence of two subscribing witnesses.

WALTER E. TRENT.
